Joseph Hackett is Design for Coal Stove.

Patented July 29, 1856.

Fig. 817.

Des. 817

Joseph Hackett of Louisville Ky.
Letters Patent No. 817, dated July 29, 1856

The schedule referred to in these Letters Patent and making part of the same

To all whom it may concern;

Be it known that I, Joseph
Hackett of Louisville, in the County of Jefferson and State

of Kentucky, have invented or produced a new and original design for a Cook Stove, designated as the "Crystal Palace"; and I do hereby declare that the following is a full, clear, and exact description of the same, reference being had to the annexed drawings making a part of this specification, in which,

Fig: 1, is a front view, and

Fig: 2, a side view of a Cook stove, showing my design.

The doors A, A, on the front of the stove, see fig 1, have each an elliptical or oval shaped projection (a), on their panels, the edges of which projections have diamond projections (b) formed all around them, near their edges. - The centres of the projections (a), have egg shaped projections (c), upon them, around which, curved corrugations (d), are formed, the outline or edge of the whole number of corrugations forming an oval.

The panels (e), at the sides of the stove, have circular projections (f) upon them, around the edges of which, diamond projections (g) are formed, and circular projections formed of curved corrugations (h), having a smooth centre (i) formed at the centres of the projections (f), see fig: 2, in which the panel on one side of the stove is shown.

On the door B, of the oven, a view of the New York Crystal Palace is shown in relief, see Fig 2.

I claim the configuration and arrangement of the ornaments herein described, the whole forming a new and original design for a Cook stove.
